SCOTLAND.

CAP AND RING SPINNING AND LIKE FRAME.

Application filed February 4, 1926, Serial No. 35,814, and in Great Britain February 7, 1925.

Our invention refers to cap and ring spinning and like frames and has for its object improvements in mechanism for effecting doffing and allied operations.

According to the invention there is provided for carrying the bobbins in spinning position a set of bobbin-carriers each rotatable upon a horizontal axis in front of or behind the line of spinning whereby full bobbins may be moved from spinning position and empty bobbins moved into spinning position. Axles on which the carriers are mounted to rotate are bored axially for passage of a rod or member for operating yarn severing devices after doffing or for effecting other doffing operations. Cap tubes or ring spindles carrying the bobbins are mounted upon the carriers, each tube or spindle in spinning position being driven by a tape wrapping a wharve on the under side of the carrier, the wharve being thus overhung to permit downward shift of the tape from the wharve on to a temporary holder, such as a loose pulley, during doffing.

The tape is shifted from the wharve to the loose pulley preferably by reversing the driving cylinder which ensures the unwinding of sufficient yarn from the spinning bobbin to prevent breakage in doffing.

When a set of bobbins is filled, by turning the carrier the full bobbins are moved away from spinning position and empty bobbins moved into spinning position. Then the threads extending from the full bobbins are given one or more turns around the empty bobbins, and are cut and spinning is resumed.

In the accompanying drawing, Fig. 1 is a diagrammatic part elevation part section showing part of a spinning frame according to the invention; Figs. 2 to 7 are detail views, Figs 2 and 3 showing a traverse poker 8, Fig. 4 a notched rotary disc, Fig. 5 axles on which carriers are mounted and Figs. 6 and 7 yarn severing devices.

Referring to the drawings, 1 denotes a horizontally disposed top rail extending along the rear side of the frame. In front of the top rail 1 is a thread board 2 with guides such as 3 through which the threads 4 to be spun pass from the drawing roller. Vertically below each guide 3 is mounted a cap spindle 5 at the upper end of which is a cap 6. The lower end 5¹ of the cap spindle 5 is fixed in a cap spindle rail 7 disposed

horizontally parallel with the top rail 1, and at a suitable distance below the board 2. At a suitable distance in front of and below the caps 6 is mounted in bearings 10² a set of traverse pokers 8 suitably spaced apart and having at their upper ends bearings 9 disposed horizontally parallel with the top rail 1. The pokers 8 are adapted to be traversed up and down by ordinary traverse mechanism. In the bearings 9 are fitted axles 10 with axial bores 10¹. On the axles 10 between adjacent pokers 8 is mounted a rotatable bobbin carrier 11 which acts as a lifting rail to traverse the spinning bobbin 12 up and down into and out of the cap 6. The bobbin carrier 11 is constructed with spaced back and front rails 11¹ and 11² integral with bosses 11³ embracing the axles 10, the rails 11¹ and 11² having horizontal top and bottom faces and being equidistant from the axles 10 on which the carrier 11 is adapted to revolve. On the rearward and upper side of the bobbin carrier 11 is mounted coaxial with the cap spindle 5 a cap tube 13 preferably clear of the cap spindle 5. The cap tube 13 is mounted in a bearing 14 in the bobbin carrier 11 and extends upwards to a suitable height. Just clear of the bearing 14 is mounted on the cap tube 13 a disc 15 with feathers 15¹ on its upper side to drive the spinning bobbin 12. On the periphery of the disc 15 is formed a notch 15² to catch and wind the yarn from the doffed bobbin around the cap tube, as hereafter explained. On the under side of the disc 15 a groove 15³ is formed to receive the yarn. The cap tube 13 extends downwards through its bearing 14 and on its lower end is mounted a wharve 13¹ by which the cap tube 13 is driven by a tape 16 in usual manner. On the cap spindle 5 below the wharve 13¹ is mounted a loose pulley 17 supported on the cap spindle rail 7. On the front and under side of the carrier 11 at the same distance from the axles 10 as the tube 13 is mounted a cap tube 13^A (similar to the tube 13) with its wharve 13^A on top. On this cap tube 13^A is mounted an empty spinning bobbin 12^A. When the spinning bobbin 12 in spinning position is full, the frame is stopped, the cap 6 is gripped at its upper end by the forked lever 6¹ hinged on the top rail 1, the driving cylinder, not shown, is reversed by hand and the tape 16 shifted from the wharve 13¹ 110

of the working cap tube 13 on to the loose pulley 17. The cap spindle 5 and the rail 7 with the loose pulley 17 and tape 16 are then lowered by rotation of a shaft 18 carrying a pulley 18¹ wrapped by a chain 19 to make room for the bobbin carrier 11 to perform a semi-rotation, whereby the full bobbin 12 and cap tube 13 are carried to the position until now occupied by the empty bobbin 12^A and its cap tube 13^A which by the same movement are carried into spinning position. As the cylinder is reversed to ship the tape 16 on to the loose pulley 17, the full spinning bobbin 12 is also rotated 15 backwards and sufficient yarn is unwound to permit the full bobbin to be carried to doffing position. The cap spindle 5 and rail 7 with the loose pulley 17 are then raised and the cap 6 seated on its spindle 5, and 20 its holder removed. The cylinder is then turned by hand in the usual direction to cause the tape 16 to rise from the loose pulley 17 on to the wharve 13¹. As the wharve 13¹ and therewith the cap tube 13 25 are rotated the disc 15 is caused to catch the thread extending from the guide 3 to the full bobbin to wind it around the cap tube 13^A which is now ready to resume spinning. On the rail 7 is mounted at a suitable height 30 and in suitable position a rod 20 extending along the under side of the bobbin carrier 11. The rod 20 guides the yarn from the full bobbin across the path of one of two yarn cutters by which the yarn is severed 35 prior to the restarting of the frame. Each yarn cutter comprises a horizontal plunger 21 mounted on the bobbin carrier 11 and sliding in a half tube 23. The half tube is formed with a gap and the plunger has a 40 notch 24 into which the yarn is guided at doffing by the rod 20. Through the bores 10¹ in the axles 10 extends a rod 25 from which a cross pin 26 enters each plunger 21. When the rod 25 is moved endways, the relative plunger 21 severs the thread at each 45 spindle.

What we claim is:—

1. In a cap or ring spinning frame or the like a carrier rotatable on a horizontal axis and presenting bearings on opposite sides of said axis, core-elements rotatable in said bearings, and a driving wharve connected to each core-element and movable therewith and with its bearing from spinning to doffing position.
2. In a cap or ring spinning frame or the

like, a carrier, horizontal axle members on which said carrier is rotatably mounted, said members having axial bores, said carrier presenting bearings on opposite sides of 60 said axle members, core elements rotatable in said bearings, a driving wharve connected to each core-element and movable therewith and with its bearing from spinning to doffing position, and means passing through the 65 bores of said axles and movable to effect a doffing operation.

3. In a cap or ring spinning frame or the like, driven bobbins, bearings for said bobbins, overhung wharves connected to said 70 bobbins and movable with said bobbins and their bearings from spinning to doffing position, and means supported by the frame separately from and below said wharves to receive a transmission element when shifted 75 from a wharve for doffing.

4. In a cap or ring spinning or like frame, in combination, a bobbin carrier rotatable on a horizontal axis and presenting bearings, bobbins sustained by said bearings, 80 bobbin driving wharves movable with said bobbins and their bearings from spinning to doffing position on rotation of said carrier, and means for driving the wharves in spinning position but disengageable from 85 said wharves when said wharves are moved from spinning to doffing position.

5. In a cap or ring spinning or like frame, in combination, a movable bobbin carrier presenting bearings, bobbins sustained by 90 said bearings, bobbin driving wharves shiftable with said bobbins and their bearings from spinning to doffing position, and means for driving the wharve in spinning position, said means adapted to be reversed to cause 95 thread to be unwound from a full bobbin before shifting from spinning position to doffing position.

6. In a cap or ring spinning frame or the like, a bearing member, a spindle, a tube 100 surrounding said spindle and rotatable in a bearing in said member, an overhung tape-driven wharve connected to said tube and movable with said tube and its bearing from spinning to doffing position, and a separate tape-receiving member below said 105 wharve to receive the tape during doffing.

In testimony whereof we have signed our names to this specification.
